United States Patent Office.

SIDNEY S. TURNER, OF WESTBOROUGH, MASSACHUSETTS, ASSIGNOR TO HIMSELF AND WILLARD COMEY, OF SAME PLACE.

Letters Patent No. 94,046, dated August 24, 1869.

IMPROVEMENT IN SEWING-MACHINE.

The Schedule referred to in these Letters Patent and making part of the same.

To all whom it may concern:

Be it known that I, SIDNEY S. TURNER, of Westborough, in the county of Worcester, and State of Massachusetts, have invented a certain new and useful Machine for Sewing Straw; and I do hereby declare that the following is a full and exact description thereof, reference being had to the accompanying drawings, and to the letters of reference marked thereon.

The nature of my invention consists in the combination and arrangement of parts, which can only be understood by an examination of the specification and drawings.

To enable others skilled in the art to make and use my invention, I will proceed to describe its construction and use.

Drawings.

Figure 1 is a perspective view, showing the front of my machine.

Figure 2 is a longitudinal section of my machine.

Figure 3 shows the needle and hook, as they appear above the stock, the hook about seizing the thread, preparatory to drawing it back through the stock.

Figure 4 shows the hook, as it appears after having drawn the thread down through the stock, the looper D about entering the loop thus formed. The section at 3' of the hook shows a groove made in the back of said hook, which serves to guide the looper, and thus cause it to enter between the threads forming the loop.

Figure 5 represents the needle and hook, set so as to form a larger angle. This arrangement would require an auxiliary looper, W, or its equivalent, for the purpose of holding the thread or loom from the needle until the hook can enter.

I construct my machine as follows:

M, fig. 2, is the main shaft, which carries the face-cams E¹ C¹, and cams H¹ D¹.

E¹ is the needle, attached to the needle-carrier E¹, which reciprocates in the bracket E, and is actuated by the cam E¹, fig. 2, which communicates its motion through the arm E², shaft E¹, and arm E².

C¹ is the hook, attached to the hook-carrier C¹, which reciprocates in the bracket C, and is actuated by the cam C¹, which communicates its motion through the arm C², hollow shaft C¹, and arm C².

H¹ and H² are feed-rollers, to which motion may be communicated by the cam H¹ actuating a ratchet, to impart an intermittent motion to the gears H¹, H², and H¹, or by any other suitable device.

The looper D, figs. 1 and 4, is operated by the cam D¹ and lever D², fig. 2.

The spool-carrier F, fig. 1, is attached to the arm E¹, so that the spool F¹ partakes of the motion of the needle E¹.

F² is a tension-spring, so arranged that it will bear upon the spool, and thus cause the necessary tension, unless it is held back by the stationary cams F³ F⁴. As the spool vibrates with the needle, it will be seen, that by proper adjustment of the cams or wedges F³ F⁴, the tension may be on or off from the thread, as required.

The bar K acts, in combination with the feed-roll H, as a presser-foot.

The upper feed-roll H is rabbeted, so that it serves as a presser-foot for both strands of the straw, the shoulder of the rabbet serving as a guide for the upper strand, thus keeping it in proper relative position with the lower strand, which is guided by a fixed gauge for sewing.

My machine operates as follows:

The two strands or braids of straw to be sewed are placed on the feed in such a manner that the lower strand rests against the fixed guide, while the upper strand is in the rabbet of the wheel H.

The needle E¹ first advances, carrying the thread up through the stock, the tension being on the thread. When the needle has passed through sufficiently far, the tension is thrown off, and the needle begins to retreat, thus forming a loop above the stock, through which the hook C¹ passes. This stage of the operation is represented in fig. 3. Then, the needle retreats while the hook is in the loop, the tension being on, thus enabling the hook to take the loop. Now, both hook and needle retreat, the tension being off, the hook carrying the loop down through the stock, as shown in fig. 4, sufficiently far for the looper D to seize it. It is then released from the hook, and held, while the stock is being fed along, in such a position that the needle in its second movement, the tension being on, may pass through it. The looper then releases it, and all the operations are repeated as before.

What I claim as my invention, and desire to secure by Letters Patent of the United States, is—

1. The combination and arrangement of the needle E¹ and hook C¹, operating substantially as described, and for the purpose set forth.

2. The tension-spring F², in combination with the fixed cams F³ F⁴, working substantially as described, and for the purpose set forth.

SIDNEY S. TURNER.
